UNITED STATES PATENT OFFICE.

JOHN FRANCIS BARRY, OF PALOS PARK, ILLINOIS, ASSIGNOR TO THE UNDERFEED STOKER COMPANY OF AMERICA, OF DETROIT, MICHIGAN, A CORPORATION OF NEW JERSEY.

PUSHER ROD THROW ADJUSTER FOR UNDERFEED STOKERS.

Application filed July 18, 1921. Serial No. 485,775.

To all whom it may concern:

Be it known that I, JOHN F. BARRY, a citizen of the United States, residing at Palos Park, in the county of Cook and State of Illinois, have invented certain new and useful Improvements in Pusher Rod Throw Adjusters for Underfeed Stokers, of which the following is a specification.

My invention relates to means for varying the throw of a pusher-rod for an underfeed stoker, and has for its general object to provide simple, rugged and effective means operable by an easily accessible handle for varying the pusher-rod throw. To these ends my invention consists in the features of construction and combinations and arrangements of parts hereinafter set forth and claimed.

In the drawings wherein I have illustrated a single embodiment of my invention, Fig. 1 is a perspective view of pertinent fragments of an underfeed stoker construction embodying my invention; Fig. 2 is a plan view with parts broken away; Fig. 3 is a side elevation with the parts in section; Fig. 4 is a section on line 4-4 of Fig. 3; and Fig. 5 is a section on line 5-5 of Fig. 3.

In underfeed stoker construction it is common practice to have a longitudinal retort 10 supplied with fuel from a throat 11 that opens endwise thereto and that itself receives fuel from a hopper (not shown) through a top opening 12, the feed being effected by a reciprocating feed-member, 35 which includes a ram or plunger 13 reciprocating in the cylinder 14 that aligns with the throat-opening 11, the ram being connected by piston rod 15 with a piston in the steam cylinder 16. It will be understood that general provision of this character is very common although in detail the constructions may differ widely from the specific form shown.

Also it is common practice to provide in the stoker a pusher-rod 17 extending into the retort from the feed end and equipped with one or more pusher-blocks 18 of suitable form. Such a pusher-rod is quite commonly reciprocated by the feed member, as through suitable connection with the ram 13 which may, to this end, carry a downwardly extending lug 19 working in a slot 20 in the bottom of cylinder 14 and forming the portion of the feed-member which is operatively

associated with the pusher-rod 17 to reciprocate the latter. It is common, also, in this type of construction, to give the lug or arm 19 a lost-motion connection with the pusher rod 17 in some fashion that will permit variation of the amount of lost-motion allowed, so that the pusher-rod 17 may be caused to take different lengths of effective movement from zero to full-stroke-length of the ram. Means for effecting such lost-motion adjustment have usually taken forms requiring that in order to vary the setting the operator shall have direct hand-access to the pusher-rod or the ram-carried lug as, for example, in order to adjust stop-blocks longitudinally along the pusher-rod and when it is understood that these throw-adjustments for the pusher-rod may need to be frequently varied for best operation of the stoker and varied while the stoker is in full operation, it will be appreciated that mechanism for more facile adjustment is highly desirable. Also, when the fact is understood that in many installations the rams are very close together and of large size, as in heavy-duty installations, so that direct access to the point of cooperation between the pusher-rod and ram-lug is both difficult and dangerous, the desirability that now and long since has existed for providing readily accessible means to control the adjustment at such inaccessible points will be realized. An embodiment of my invention, which satisfies these desiderata, I will now describe in detail.

The rear end of pusher-rod 17 is flattened to provide a bearing surface for a pivoted adjusting stop and is provided with a retraction-stop that cooperates with ram-lug 19 to cause the rod invariably to be retracted to the same position whether its forward throw be great or little. Specifically, the rod has bolted to its rear end flat extension plates 22, 22', forming sides of a yoke closed at its rear end by the retraction-stop 23 and receiving the ram-lug 19 in the vertical slot 24, this slot being preferably substantially equal in length to the range of travel of ram-lug 19. The flat tops of the bars 22, 22' form a guide surface for the adjustable stop 25 which is pivoted at its forward end, as at 25', upon the solid block-portion of the pusher-rod structure, which is formed where the squared extremity 17' of the rod proper is bolted to the extension plates. This stop

is provided with a suitable series of steps 26 which the treads or receptive surfaces of which may respectively be brought into register with the slot 24 by pivotally swinging the stop structure, thereby leaving a greater or less portion of the slot 24 open to permit of lost-motion between the ram and the pusher-rod since, of course, the ram will travel idly in one direction along the pusher-rod until its lug 19 encounters that step of stop 25 which overlies slot 24.

The manner of supporting the yoke-bearing end of rod 17 may be varied, but preferably lug 19 carries anti-friction roller means 27 projecting laterally under the yoke-sides 22, 22' to afford requisite support for the pusher-rod.

To vibrate the adjustable stop 25 on its pivot and hold it in adjusted position I preferably provide a hand-lever 28 extending above the ram and steam cylinder for easy accessibility, and preferably pivoted to a fixed support. Such lever I connect to the adjustable stop 25 by means that will not interfere with the reciprocatory movement of the adjustable stop but that will maintain constant controlling connection therewith in a fashion uniform throughout the reciprocatory travel of the stop. Specifically, the lever structure 28 includes a handle proper 29 and a bail portion 30, preferably made of a continuous piece of rod-stock bent to provide portions 31, 31' pivoting in longitudinal alignment in ears 32, 32' that are secured to convenient portions of the ram cylinder 14, such bail including, between and below its pivoted ends, the longitudinal slide-bar 33. This bar is embraced in the vertical slot 34 of a link structure 35 which is pivoted as at 36 to the free extremity of the adjustable stop. This link is preferably forked to receive the laterally offset end of the stop 25 and to be carried in horizontal position, and its slotted head is preferably elongated 45 in the direction of length of the bail-bar 33 so as to give a very substantial bearing for the operation of said bar. With the handle portion 29 of the hand-lever there coacts a segment 37 secured to some suitable fixed 50 part such as the head of steam cylinder 16 and provided with lever-positioning notches 38 into which the somewhat resilient lever-rod may be sprung for self-retention in adjusted position.

Manifestly, as one throws the hand-lever to the right (Fig. 1) the bail-rod 33 is thrown to the left, carrying with it the link 35 and adjustable stop 25, to change the setting of said stop for increase of lost-motion between the pusher-rod 17 and the ram-lug 19, while throwing the handle to the extreme left end of its segment 37 minimizes the lost-motion permitted by the resultant in-swinging of the stop 25. The length of the bail-bar 33 is sufficient to permit full reciproca-

tion of the link 35 and the height of slot 34 accommodates the vertical displacement of bail-bar 33 incident to its pivotal movement.

While I have herein described in some detail a particular embodiment of my invention for purposes of disclosure, it will be understood that I do not intend thereby to limit my invention to the specific details shown further than as specified in the claims, and that many changes in construction may be made without departure from the spirit of the invention within the scope of the appended claims.

I claim:

1. The combination with an underfeed-stoker ram and a pusher-rod to be operated therefrom, of a part positively movable by said ram, a stop mounted on said rod and movable for interposition in the path of said positively movable part to intercept the latter at different points along the pusher-rod, a hand-lever movable to several positions, means for latching said hand lever in any selected one of said positions, and operative connections between said lever and said stop for adjustment of the latter by the former in any position to which said stop may be moved with said pusher-rod.

2. The combination of a reciprocating feed member and a reciprocable pusher-rod, of multi-stepped means carried by one thereof adjustable to permit respective ones of its several steps to coact with the other thereof and thereby permit selectively-variable lost-motion between the feed member and the pusher-rod, an operating lever movable to several positions corresponding with the respective steps, and positive operative connections between said lever and said stepped means constantly conditioned to adjust said stepped means for the purpose set forth.

3. The combination with a stoker-ram and lug, and a pusher-rod, of a pivoted, multi-stepped adjustable stop carried by the pusher rod, a hand lever pivoted to a stationary part of the stoker, and positive operating connections between said hand lever and said adjustable stop for adjusting said stop in any position to which it may be carried by said pusher rod, thereby to interpose any step of said stop in the path of said lug.

4. The combination with a ram and a part positively movable thereby, of a pusher rod, a rod-retracting stop carried thereby and arranged in the path of movement of said positively movable part, a stepped rod-advancing stop pivoted on the pusher-rod and movable to interpose any selected step in the path of movement of said positively movable part, an operating lever having a bail extension that parallels the pusher-rod, and an operative positive connection between said bail-extension and said adjustable stop, adapted to move the latter in any position

to which it may be carried by the pusher-rod.

5. A structure as defined in claim 4, wherein said operative connection between the bail extension and the adjustable stop comprises a link mounted on one of said members and having operative connection with the other of said members, said connection permitting relative motion in one plane between said link and the latter member.

6. A structure as defined in claim 4, wherein the adjustable stop is pivoted on a vertical axis to the pusher-rod and the operative connection between the bail extension and the adjustable stop comprises a vertically slotted part embracing the bail extension and carried by the adjustable stop. 15

JOHN FRANCIS BARRY.
